UNITED STATES PATENT OFFICE

MAX KUPFERSTOK, OF NEW YORK, N. Y.

DESIGN FOR AN EMBLEM PLATE OR SIMILAR ARTICLE

Application filed April 22, 1931. Serial No. 39,594. Term of patent 3½ years.

To all whom it may concern:

Be it known that I, MAX KUPFERSTOK, a citizen of the United States, residing at New York city, in the county and State of New York, have invented a new, original, and ornamental Design for an Emblem Plate or Similar Article, of which the following is a specification, reference being had to the accompanying drawing, forming a part thereof, in which;

The figure is a plan view of the emblem plate showing my new design, it being understood that the device is thin and flat.

I claim

The ornamental design for an emblem plate or similar article, as shown and described.

MAX KUPFERSTOK.
